DESIGN FOR A BRACELET

Alfred Philippe, New York, N. Y.

Application September 15, 1941, Serial No. 103,352

Term of patent 3½ years

To all whom it may concern:

Be it known that I, Alfred Philippe, a citizen of the United States of America, residing in New York city, county of New York, and State of New York, have invented a new, original, and ornamental Design for a Bracelet, of which the following is a specification, reference being had to the accompanying drawing, forming part thereof.

Fig. 1 is a plan view of a bracelet, showing my new design.

Fig. 2 is an edge view thereof.

I claim:

The ornamental design for a bracelet substantially as shown.

ALFRED PHILIPPE.
